US0D1098626S

(12) United States Design Patent (10) Patent No.: US D1,098,626 S
(45) Date of Patent: * Oct. 14, 2025

(54) PET HAIR BRUSH WITH A REMOVABLE COVER

(71) Applicant: Shenzhen KIWI Design Co., Ltd.,
Guangdong (CN)

(72) Inventor: Zhinan Zhang, Guangdong (CN)

(73) Assignee: Shenzhen KIWI Design Co., Ltd.,
Shenzhen (CN)

() Term: 15 Years

(21) Appl. No.: 29/887,785

(22) Filed: Mar. 24, 2023

(30) Foreign Application Priority Data

Dec. 23, 2022 (CN) 202230857984.0
